UNITED STATES PATENT OFFICE.

THOMAS C. STEEN, OF LAKE CHARLES, LOUISIANA.

DESIGN FOR A TOY TELEPHONE.

57,022.

Specification for Design.

Patented Jan. 25, 1921.

Application filed June 14, 1920. Serial No. 389,035. Term of patent 3½ years.

To all whom it may concern:

Be it known that I, THOMAS C. STEEN, a citizen of the United States, residing at Lake Charles, in the parish of Calcasieu and State of Louisiana, have invented a new, original, and ornamental Design for Toy Telephones, of which the following is a specification, reference being had to the accompanying drawing, forming part thereof.

Fig. 2 is a similar view looking toward the opposite side, and
Fig. 3 is a front elevation.

I claim:

The ornamental design for a toy telephone, as shown.

THOMAS C. STEEN.
